SKI-SHOE

Jean-Louis Barrault, Paris, France, assignor to
Le Trappeur Sillans, Isere, France

Filed Aug. 20, 1970, Ser. No. 24,603

Claims priority, application France May 5, 1970

Term of patent 7 years

Int. Cl. D2—04

U.S. Cl. D2—276

FIG. 1 is a top plan view of a ski-shoe showing my new design;

FIG. 2 is a bottom plan view thereof;

FIG. 3 is a front elevational view;

FIG. 4 is a rear elevational view;

FIG. 5 is a side elevational view taken from the left of FIG. 4; and

FIG. 6 is a side elevational view taken from the right of FIG. 4.

I claim:

The ornamental design for a ski-shoe, as shown.
